BINOCULAR HOLDER

Thomas H. Horst, Lafayette, Colo., assignor to Western Sales and Supply Co., Denver, Colo.

Filed Aug. 7, 1972, Ser. No. 278,590

Term of patent 14 years

Int. Cl. D6—99

U.S. Cl. D6—28

FIG. 1

FIG. 2

FIG. 3

FIG. 4

FIG. 5

FIG. 1 is a front elevation view of the binocular holder of the present invention;

FIG. 2 is a front elevation thereof;

FIG. 3 is a left side elevation view;

FIG. 4 is a top plan view; and,

FIG. 5 is a perspective view to an enlarged scale showing the unit as seen from a vantage point above and to the left of its front end.

The right side elevation is a mirror image of the left side elevation and the bottom is plain.

I claim:

The ornamental design for a binocular holder, as shown and described.
